2,259,500

FIRE EXTINGUISHING METHOD

Norman J. Thompson, Wellesley, Mass.

Application August 22, 1939, Serial No. 291,349

2 Claims. (Cl. 169—14)

As is well known the most difficult fires to extinguish are those of flammable liquids such as acetone, lacquers or Japanning preparations, ether, gasoline, etc., particularly in the case of exposed liquids such as pools spilled on the floor or used in open pans or vats in contradistinction to unexposed liquid such as liquid stored in a closed tank, the extinction of the exposed fires being rendered more difficult because of drafts of air, such as those induced by the fire and those resulting from open windows and the like, which increase the rate of combustion.

Objects of the present invention are to provide a fire extinguishing method which is simple and inexpensive to practice, which is reliable and economical in use, which is quick and effective in action, which can be practiced with permanent or portable apparatus over or near open vats without interfering with the normal use of the vats, which is universally applicable to all flammable liquids, which has little if any tendency to impair the quality of most flammable liquids, which permits a high proportion of salvage of unburned liquid, which has little if any tendency to flood the premises, which can be controlled either automatically by heat responsive means or manually as by hand operated valves, which does not require expensive liquids or gases, which does not require bulky fluid containers and which is generally superior to methods heretofore used, particularly for use in extinguishing fires in exposed places.

According to the present invention the fire is subjected to the direct action of a spray of discrete particles of propellant fluid such as water or water vapor, the spray preferably diverging in the form of a cone from a small nozzle opening to a substantial area, and a gaseous fire extinguisher is entrained in the spray at or near the apex of the cone. While the gaseous fire extinguisher preferably consists in whole or in part of carbon dioxide it may comprise any gaseous fluid, such as nitrogen, boiler flue gas, or internal combustion engine exhaust gas, which is sufficiently deficient in oxygen to tend to smother a fire. The gaseous fluid is preferably entrained in said spray of propellant particles by enclosing the apex of the conical spray in a casing shaped to serve as a mixing chamber. By employing a spray comprising water particles the aspirating action is fairly efficient because water particles are heavy compared with the molecules of gaseous extinguisher; consequently the mixture of water particles and gaseous extinguisher will carry considerable distances without using excessive pressure in the

aspirator nozzle. Moreover the water particles help materially to extinguish the fire, not only by their cooling effect but also by a smothering effect as they flatten upon impingement with the surface of the flammable liquid and tend to form a film over the surface of the liquid. While the spray of water particles may be formed with a jet of steam which condenses into water vapor as it emerges from the nozzle, of course the cooling effect is greater if the spray be produced with cold water. The gaseous extinguisher which is carried to the fire by the aspirating action of the water spray not only tends to displace the oxygen in the region of the fire but its presence in and around the spray tends to prevent the spray from carrying air to the fire.

For various reasons a mixture of water particles and gaseous extinguisher is superior to a spray of either water particles alone or gaseous extinguisher alone, particularly when the water particles are sprayed directly to the fire from a nozzle and the gaseous extinguisher is drawn into and around a spray of water particles by aspirating action. Such a mixture will extinguish difficult fires of certain flammable liquids such as gasoline which a water spray alone will not extinguish, and less difficult fires of flammable liquids are extinguished more quickly and at less expense. Even in those cases where water alone will extinguish the fire much more water is required, thereby resulting in more water damage. When using only gaseous extinguisher on exposed fires it is difficult to blanket the fire with the gas because of drafts, and even in cases where exposed fires can be extinguished with gas alone a relatively excessive quantity of gas is required. The propulsion of a stream of gaseous extinguisher requires high pressures, and therefore expensive high-pressure equipment; and even then the range of the stream is too limited for satisfactory use except in closed buildings. In the case of fires in open vats of flammable liquids the gas nozzles would have to be placed too close to the surface of the liquid to permit fixed installations of automatic equipment without seriously interfering with the normal use of the vats, particularly in cleansing and lacquering establishments.

For the purpose of illustration typical embodiments of the invention are shown in the accompanying drawing in which

Figs. 1 and 2 are side and front elevations of one installation;

Fig. 3 is a vertical central section through a modified aspirator;

Fig. 4 is a bottom plan view of the aspirator shown in Fig. 3; and

Fig. 5 is a view similar to Fig. 3 showing another modification.

The particular embodiment of the invention shown in Figs. 1 and 2 is illustrated in association with the vat 16 of flammable liquid, such as a tank of cleansing fluid or a vat of lacquer for example. The apparatus comprises a casing 15 which encloses a space 16 serving as a mixing chamber. The casing may be supported in any suitable way as indicated at 5. Extending downwardly through an opening in the top of the casing is a pipe 17 terminating in a nozzle 19 within the chamber 16, through which the propellant fluid, such as water or steam, may be supplied under pressure. Extending through the rear end of the casing 15 is a conduit 18 terminating in a nozzle 21 within the chamber 16, the conduit 18 leading to a cylinder 22 of liquified carbon dioxide or other suitable source of gaseous extinguisher. The lower end of the casing 15 is formed as a separate funnel-shaped part forming a flaring continuation of the upper portion of the casing. When using water as the propellant the nozzle 19 may be of any of the well-known types which break the water stream into a divergent spray of discrete particles, and when using steam the nozzle may be of any well-known type which produces a divergent spray of particles of steam.

To start the operation of the apparatus the conduits 17 and 18 are opened to admit the liquid propellant and gaseous extinguisher to the mixing chamber through the nozzles 19 and 21 respectively. Any suitable manual or automatic means may be employed to start the operation. While the spray of propellant should issue from the nozzle 19 with considerable force, the gaseous extinguisher may be supplied through the outlet 21 at a low velocity which is merely sufficient to supply the extinguisher at the desired rate. The gaseous extinguisher is carried to the fire by the force of the propellant spray, the mixing chamber 16 being shaped to cause a substantial amount of the gaseous extinguisher to be entrained in the spray of propellant particles. The size and shape of the outlet portion 20 of the casing 15 is preferably such that the divergent spray substantially fills the outlet of the casing.

In the modification shown in Figs. 3 and 4 the aspirator 25 comprises a conical mixing chamber 26, a conduit 27 for supplying the propellant, a propellant nozzle 28, a pipe 29 for supplying the gaseous extinguisher and an annular nozzle 30 having openings 31 in its lower side for emitting the extinguisher. This form of aspirator is very satisfactory when using water as the propellant.

10 The modified aspirator 35 shown in Fig. 5 comprises a cylindrical casing 36 enclosing the upper portion of a mixing chamber 37 which also includes a Venturi type outlet portion 38. The propellant is supplied through conduit 39 to the nozzle 40, and the gaseous extinguisher is supplied through the conduit 41 to the nozzle 42. This form of the invention is especially suited to the use of steam as the propellant.

15 In each of the illustrated modifications the depending flaring portion of the mixing chamber serves not only to improve the aspirating action but it also tends to enhance the down-draft of gaseous extinguisher around the conical spray, thereby counteracting the usual tendency of a spray of fluid to feed the fire with air drawn toward the fire by the spray itself.

20 It should be understood that the present disclosure is for the purpose of illustration only and that this invention includes all modifications and equivalents which fall within the scope of the appended claims.

I claim:

1. The method of extinguishing fires which comprises propelling a spray of discrete fire-extinguishing liquid particles from an orifice directly to the fire and with said spray aspirating to the fire a gaseous extinguisher between and around said particles.

2. The method of extinguishing fires which comprises propelling a conical spray of discrete fire-extinguishing water particles from an orifice to the fire and in the apex portion of said conical spray aspirating a gaseous extinguisher between and around the water particles, whereby the fire is subjected concomitantly to the cooling action of the water and the smothering action of the gaseous extinguisher.

NORMAN J. THOMPSON.
